UNITED STATES PATENT OFFICE.

GEORGE A. MORGENTHALER, OF DAYTON, OHIO, ASSIGNOR TO AUGUST POLLMANN, OF NEW YORK, N. Y.

HARMONICA-HOLDER.

SPECIFICATION forming part of Letters Patent No. 439,415, dated October 28, 1890.

Application filed June 5, 1890. Serial No. 354,335. (No model.)

To all whom it may concern:

Be it known that I, GEORGE A. MORGENTHALER, a citizen of the United States, residing at Dayton, in the county of Montgomery and State of Ohio, have invented certain new and useful Improvements in Harmonica-Holders; and I do hereby declare that the following is a full, clear, and exact description of the invention, which will enable others skilled in the art to which it appertains to make and use the same, reference being had to the accompanying drawings, and to the letters and figures of reference marked thereon, which form a part of this specification.

15 My invention relates to improvements in harmonica-holders, the features of which will be fully hereinafter described and claimed.

The object of the invention is to support a harp or other instrument within the clothing 20 of the neck in convenient position to be blown into in the production of musical sounds.

The device is illustrated in the accompanying drawings, in which—

Figure I is a fragmentary front view of the 25 device. Fig. II is a side view showing but one of the symmetrical sides.

Like letters designate like parts in the two views.

The front A is of metallic plate having the 30 curve 1 bent to the rear. Beneath this curved part are two lips 2 2. The inclination is then forward and downward in a vertical line, this part having orifices in the folds of the sides, into which the ends of the wire frame B are 35 inserted. The dotted lines 3, Fig. II, show the position of the harp as held between the top curve and the lips on the sides. The wire-supporting frame B comprises a single piece of wire bent at its center into a semicircle

extending backward, upward, and slightly 40 outward 7, bent and extending in a nearly horizontal position 6, bent downward and slightly forward 5, bent nearly in the form of a semicircle, and terminating in vertical parallel ends 4. These outer orifices are in the sides 45 of the holder-plate, and thus the two parts are joined. The plate of the holder is thin, and is easily bent to conform to the instrument to be held. The wire is of spring metal and may be sprung and bent to suit the conditions. 50

In use the part 7 is inserted within the collar or neckband, the lower bent portion resting on or about the collar-bone. This brings the top part, in which the harp is held, in close proximity to the mouth. 55

What I claim, and desire to secure by Letters Patent, is—

1. A harp or other instrument holder consisting substantially of plate A, with top curve 1 and lips 2 2, to hold an instrument, and the 60 wire support B, with loop to engage the collar-band, and downwardly-projecting parts to form a bearing and attached to said plate, substantially as shown and described.

2. The supporting-frame B of a single piece 65 of wire comprising a semicircular bend at its center extending backward, upward, and slightly outward, bent to a horizontal position, then bent in the form of a semicircle and terminating in vertical parallel ends to 70 support a holder, substantially as described.

In testimony that I claim the foregoing as my own I affix my signature in presence of two witnesses.

GEORGE A. MORGENTHALER.
